UNITED STATES PATENT OFFICE.

ARTHUR T. TIMEWELL, OF CHICAGO, ILLINOIS, ASSIGNOR TO ALBERT DICKINSON, OF SAME PLACE.

FILLED-SACK-SEWING MACHINE.

SPECIFICATION forming part of Letters Patent No. 607,810, dated July 19, 1898.

Application filed July 31, 1897. Serial No. 646,608. (No model.)

To all whom it may concern:

Be it known that I, ARTHUR T. TIMEWELL, a citizen of the United States, residing in Chicago, in the county of Cook and State of Illinois, have invented a new and useful Improvement in Filled - Sack - Sewing Machines, of which the following is a specification.

My invention relates to machines for sewing filled sacks.

- 10 Machines heretofore constructed for this purpose have usually comprised, in connection with a sewing mechanism, an opening and closing traveling sack-holder having two or more clamp-bars for holding the mouth of 15 the filled sack closed and in position for sewing as the filled sack is conveyed past the sewing mechanism, the holder also serving, in most cases, to hold the empty sack open while it is being filled.
- 20 The object of my present invention is to provide a machine of a simple and durable construction and efficient in operation by means of which filled sacks may be very rapidly and cheaply sewed as they pass continuously through the machine.

25 To this end my invention consists, essentially, in connection with a sewing mechanism of any suitable construction, of an endless traveling sack-holder comprising a pair 30 of opening and closing continuous endless flexible clamps, preferably chains, traveling on suitable pulleys or sprocket-wheels and between which the mouth edges of the filled sacks are fed and by which the same are 35 clamped and held closed in position for sewing as the continuously-traveling chains carry the sacks one after another past the sewing mechanism. Suitable guides in or along which the chains travel cause their opposing 40 or parallel portions to properly clamp the sacks between them. The pulleys at the front end of the machine around which the chains pass, or, rather, the curved portions of the chains on these pulleys, serve to feed the 45 mouth edges of the sacks in between the chains as soon as the front edge of the sack-mouth is placed in the bite thereof, just as a sheet, for example, passes between rollers revolving together. A conveyer is or may be 50 employed to convey the filled sacks to this endless traveling sack-holder. In cases where

the material of which the sacks are made is not strong enough to safely sustain the weight of the filled sack by suspension by its mouth edge from the endless traveling sack-holder 55 I employ a traveling sack-conveyer for the filled sacks to rest upon while being conveyed through the machine, and this same conveyer may be extended so as to serve also as the means for conveying the filled sacks to the 60 machine and for delivering them from it after being sewed. The backs or meeting faces of the links of the endless chains comprising the endless traveling sack-conveyer are provided the one with a groove and the other with a 65 rib or tongue fitting in the groove to increase their clamping or holding action upon the mouth edges of the sacks. The filled sacks should be delivered to the machine one after another and continuously passed through the 70 machine with intervals of only a few inches, preferably five or six, between the successive sacks, and the chain of stitching or thread uniting the successive sacks is cut by a suitable knife or cutter, which is or may be operated by each sack as it passes by a movable 75 lever projecting in the path of the sack.

In the accompanying drawings, forming a part of this specification, Figure 1 is a side elevation of a machine embodying my invention. Fig. 2 is a plan view. Fig. 3 is a partial vertical section on line 3 3 of Fig. 2. Fig. 4 is a detail plan view of a portion of the chain. Fig. 5 is a section on the line 5 5 of Fig. 2, and Fig. 6 is a detail of the knife or 85 cutter.

In the drawings like letters of reference indicate like parts in all the figures.

In said drawings, A represents the frame of the machine. The bed-plate A', upon 90 which the sewing mechanism B is mounted, is provided with a longitudinal slot a for the mouth edges of the sacks to project through as they are being conveyed past the sewing mechanism.

95 The endless traveling sack-holder D consists, preferably, of two continuous endless flexible opening and closing chains d d, each traveling on suitable pulleys or sprocket-wheels d' d' and guided at their opposing parallel portions by suitable guides C C, extending along the slot a, one on each side thereof,

so as to cause them to properly clamp and hold the mouth edges of the filled sacks between them. The links of the two chains d of the endless traveling sack-conveyer are provided at their backs or meeting faces the one with a groove d^2 and the other with an interfitting tongue or rib d^3 to increase their clamping action upon the mouths of the sacks. The two chains of the endless traveling sack-holder are propelled or driven continuously by power applied to the shaft d^4 of one of the pulleys or sprockets d' , preferably by means of a gear d^5 on said shaft meshing with a worm d^6 on the shaft d' , which is provided with a bevel-gear d^7 that meshes with a gear B' on the driving-pulley B^2 of the sewing mechanism, the two chains d being also preferably geared together by the intermeshing gears d^8 d^9 , the former being on the shaft d^4 of the sprocket-wheel of one chain and the latter on the shaft d^{11} of the sprocket-wheel of the other chain. The guides C for the chains d should be shaped to fit the inner faces of said chains, so as to properly guide or hold them in position, especially in cases where the weight of the filled sack is designed to be suspended or supported from and by the endless traveling sack-holder, as may be readily done in operating upon small sacks—such, for example, as ten or twenty-five pound sacks—or upon larger sacks composed of strong fabric, such as are commonly used for bagging grain.

Bridges A^2 A^3 , spanning the slot a , unite the two portions of the bed-plate A' of the frame on each side of said slot.

F is a carrier consisting, preferably, of an endless traveling platform running upon rollers or sprockets F' , upon which the filled sacks X are placed and by which they are conveyed to the machine in position to have their mouth edges x inserted between the front pulleys d d' and sack-holder chains d d . This same conveyer F is also preferably extended through the machine under the straight or parallel portions of the sack-holding chains d d , so that in cases where necessary the weight of the filled sacks may be in whole or in part supported by this conveyer. While the sacks are being conveyed through the machine. By this means the endless traveling sack-holder D is or may be relieved from the weight of the filled sack. The conveyer F is also preferably further extended at the rear of the machine, so that it may also serve as the means for conveying or delivering the filled and sewed sacks out of or from the machine.

To readily adapt the same machine to operate upon filled sacks of different sizes, heights, or lengths, the bed-plate A' , upon which the sewing mechanism B and endless traveling sack-holder D are mounted, is provided with telescopic or extension legs or supports A^4 A^5 , so that the height of the bed-plate A' above the conveyer F may be adjusted as required. Set-screws A^6 serve to fix the movable legs A^4

in any position desired in respect to the stationary legs A^5 .

The sewing mechanism B may be of any suitable construction known to those skilled in the art and requires no detailed description, as my invention does not consist in nor is it dependent upon any particular construction of sewing mechanism. The particular form of sewing mechanism which I have for convenience illustrated in the drawings comprises a frame or arm B^3 , attached to the bed-plate A' of the frame at one side of the slot a and overhanging said slot and the guides C C and parallel portions of the sack-holder chains d d , and a needle b , looper b' , and presser-foot b^2 , and suitable gearing or mechanism for communicating motion to the needle and looper.

From the continuously-rotating driving-pulley B^2 motion is communicated to the sewing mechanism through a friction-clutch B^4 B^5 .

G is the knife or cutter by which the chain of stitching or thread x' uniting the sewed sacks is cut as each sack passes. The cutter is mounted upon and operated by a lever G' , the free end of which projects normally in the path of the sack and which is caused to move in and carry the knife G against the chain of stitching x' the moment the sack passes by a spring G^2 . Opposing cutters or pins g g , projecting downwardly from the table A' , facilitate the action of the knife G in cutting the thread or chain of stitching.

One of the guides C C is adjustably secured to the bed-plate A' , so that it may be moved or adjusted to or from its fellow for the purpose of regulating the gripping or clamping action of the opposing sack-holder chains upon the sacks. It is so adjustably fixed in position by adjusting screws C' in connection with bolts C^2 , which latter pass through the guide C and the table A' , slots being provided in the one or the other to permit of the adjustment.

While I have called the two opposing endless parts of the endless traveling sack-holder "chains" and have illustrated them in the drawings as being composed of links, I wish it to be understood that by use of the word "chains" I mean to include any form of endless flexible belts or connections suitable for use in my combination.

The conveyer F may be driven by any suitable mechanism. It should, however, be driven at the same speed as that of the traveling-sack-holder chains d d . This may preferably be done by connecting it directly with the shaft d^4 , through which motion is imparted to the chains d d . It may be so connected by any suitable connecting mechanism or gearing—such, for example, as that indicated in the drawings.

H is a belt-shifter for starting and stopping the machine by shifting the driving-belt from the loose pulley E' , which is not connected to the machine, to the pulley B^2 , which is connected to the machine.

H' is a clutch-rod for operating the friction-clutch B⁴ B⁵, by which the driving-shaft of the sewing mechanism is connected to the driving-pulley B². By means of these two clutch-rods the sewing mechanism may be started or stopped independently of the sack-holder chains d d.

I claim—

1. In a machine for sewing filled sacks, the combination with a sewing mechanism of an endless traveling sack-holder comprising a pair of opening and closing endless flexible clamps for receiving and feeding the mouth edges of the filled sacks and holding the same closed in position for sewing, and conveying the same past the sewing mechanism, substantially as specified.

2. A filled-sack-sewing machine, comprising in combination a sewing mechanism and an endless traveling sack-holder comprising a pair of opening and closing continuous endless flexible clamps, substantially as specified.

3. A filled-sack-sewing machine, comprising in combination a sewing mechanism and an endless traveling sack-holder consisting of a pair of endless chains having opposing parallel portions between and by which the mouth edges of the sack are received, fed, clamped and held, substantially as specified.

4. In a filled-sack-sewing machine, the combination with a sewing mechanism, of a pair of endless chains having opposing parallel portions between and by which the sacks are received, fed and clamped, the backs or meeting faces of said chains having the one a groove and the other an interfitting tongue to increase the clamping or holding action of the chains upon the sacks, substantially as specified.

5. In a filled-sack-sewing machine, the combination with a sewing mechanism, of an endless traveling sack-holder comprising a pair of opening and closing continuous endless flexible clamps, and a conveyer for delivering the filled sacks to the endless traveling sack-holder, substantially as specified.

6. In a filled-sack-sewing machine, the combination with a sewing mechanism of an endless traveling sack-holder comprising a pair of opening and closing continuous endless flexible clamps and a conveyer for supporting the weight of the filled sacks as they are carried through the machine past the sewing mechanism, substantially as specified.

7. In a filled-sack-sewing machine, an endless traveling opening and closing continuous sack-holder consisting of a pair of endless chains having parallel opposing portions traveling together and between which the sacks are clamped, substantially as specified.

8. In a filled-sack-sewing machine, an endless traveling opening and closing continuous sack-holder consisting of a pair of endless chains having parallel opposing portions traveling together and between which the sacks are clamped, and guides for the parallel portions of said chains, substantially as specified.

9. In a filled-sack-sewing machine, the combination with a bed-plate having a longitudinal slot a, of a sewing mechanism, and a pair of endless traveling sack-holder chains, guides C C, and pulleys or sprocket-wheels upon which said endless chains travel, whereby the filled sacks are automatically received, fed and clamped between and delivered from said chains, substantially as specified.

10. In a filled-sack-sewing machine, the combination with the sewing mechanism, of an endless traveling sack-holder comprising a pair of opening and closing continuous endless flexible clamps, and a knife or cutter for severing the chain of stitching or thread uniting the sewed sacks as they pass successively through the machine, substantially as specified.

11. In a filled-sack-sewing machine, the combination with the sewing mechanism, of an endless traveling sack-holder, a knife or cutter for severing the chain of stitching or thread uniting the sewed sacks as they pass successively through the machine, and an arm or lever projecting in the path of the filled sack for operating said knife or cutter, substantially as specified.

12. The combination with a sewing mechanism, of a pair of endless traveling sack-holder chains adapted to receive and feed the mouth edges of the sack between them, and a conveyer for delivering the sewed sacks from the machine, substantially as specified.

13. A filled-sack-sewing machine, comprising in combination a sewing mechanism and an endless traveling sack-holder consisting of a pair of endless chains having opposing parallel portions between and by which the mouth edges of the sack are fed, clamped and held, and guides for the parallel portions of said chains, substantially as specified.

14. A filled-sack-sewing machine, comprising in combination a sewing mechanism and an endless traveling sack-holder consisting of a pair of endless chains having opposing parallel portions between and by which the mouth edges of the sack are fed, clamped and held, and guides for the parallel portions of said chains, one of said guides being adjustable to and from its fellow, substantially as specified.

15. In a filled-sack-sewing machine, the combination with the sewing mechanism, of an endless traveling sack-holder, a knife or cutter for severing the chain of stitching or thread uniting the sewed sacks as they pass successively through the machine, and an arm or lever projecting in the path of the filled sack for operating said knife or cutter by engagement with the sewed sack as it passes, substantially as specified.

ARTHUR T. TIMEWELL.
